18 Claims. (Cl. 260—683.5)

This invention relates to an isomerization process and more particularly to the isomerization of saturated hydrocarbons in the presence of hydrogen.

It is frequently desirable to isomerize saturated hydrocarbons such as the paraffinic and naphthenic hydrocarbons and convert one isomer to another. For example, n-heptane or n-octane are poor fuels for internal combustion engines, whereas the isoheptanes or iso-octanes are excellent motor fuels. Accordingly, in the compounding of motor fuels, it is desirous to convert n-heptane into isoheptanes or n-octane into iso-octanes.

Again in the case of the butanes, isobutane is suitable for alkylation and can be alkylated with an olefin to form an excellent motor fuel. On the other hand, n-butane cannot be alkylated by conventional procedures to form a satisfactory motor fuel. It is therefore seen that it is desirable to isomerize n-butane to isobutane. Moreover, it is desirable to isomerize methylcyclopentane to cyclohexane. The cyclohexane can then be oxidized to adipic acid, which finds great utility in the manufacture of plastics, such as nylon.

The process of the instant invention relates to an improvement in an isomerization process in which a saturated hydrocarbon is isomerized in the presence of hydrogen at a temperature of about 700° to 1100° F. and a pressure in excess of about 50 pounds per square inch. There is no appreciable consumption of the hydrogen during the course of the process. The isomerization is conducted in the presence of a solid catalyst, conventional hydrogenation catalysts being suitable for this purpose. We have discovered that by incorporating in the charge, in accordance with our invention, a polynuclear condensed ring compound of the class disclosed below, cracking during the isomerization is effectively inhibited. The condensed ring compound is selected from the group consisting of the trinuclear carbocyclic aromatic compounds, the trinuclear heterocyclic nitrogen aromatic compounds, and the hydrogenated derivatives of compounds of the above classes. The amount of the added cracking inhibitor should not be more than 5 percent by weight of the saturated hydrocarbon and is usually of the order of 0.1 to 3 percent. Preferably, the concentration of cracking inhibitor should be adjusted so that it is in vapor phase at the reaction conditions.

The cracking inhibitor is preferably added to the saturated hydrocarbon prior to the heating of the saturated hydrocarbon to the isomerization temperature of about 700° to 1100° F., and at temperature below the isomerization temperature. This procedure has the advantage of retarding thermal cracking of the saturated hydrocarbon. Moreover, it is also to be preferred, particularly in the case of high molecular weight hydrocarbons, to maintain the partial pressure of the hydrogen at the reaction pressure in excess of 50 percent of the total pressure.

The feed employed in the process of our invention

comprises a saturated hydrocarbon. The feed may be a pure saturated hydrocarbon such as n-butane or a mixture of saturated hydrocarbons such as a mixture of n-butane, n-pentane and n-hexane. Where the feed is a saturated paraffinic hydrocarbon, it is desirable to isomerize a feed comprising a straight chain hydrocarbon such as n-butane, n-heptane or n-octane. However, the process of our invention is equally applicable to the isomerization of branched chain saturated hydrocarbons such as the isomerization of 2-methyl-heptane to 2,4-dimethyl hexane. Moreover, the process of our invention is also applicable to the isomerization of naphthenic hydrocarbons, such as the isomerization of methylcyclopentane to cyclohexane. The preferred feeds in the process of our invention comprise the straight chain saturated paraffinic hydrocarbons having from 4 to 12 carbon atoms.

As heretofore mentioned, the cracking inhibitors employed in the process of our invention comprise polynuclear condensed ring compounds. In particular, these cracking inhibitors include trinuclear carbocyclic aromatic compounds such as anthracene and phenanthrene and also the hydrogenated derivatives of these compounds such as octahydroanthracene. Additional cracking inhibitors which can be used in the process of our invention include binuclear heterocyclic nitrogen aromatic compounds such as quinoline, isoquinoline, and indole, as well as hydrogenated derivatives of these compounds such as hexahydroquinoline. Further cracking inhibitors which can be used in the process of our invention include trinuclear heterocyclic nitrogen aromatic compounds such as acridine, carbazole, phenanthridene, phenazine, phenanthroline, and the hydrogenated derivatives of these compounds such as octahydroacridine. The cracking inhibitors can comprise pure compounds such as those mentioned above, or mixtures of pure compounds such as a mixture of anthracene and acridine, or of quinoline and indole. Moreover, fuel distillate fractions containing the aforementioned cracking inhibitors can be used provided that the concentration of cracking inhibitor is maintained within the limits heretofore mentioned. Examples of these fractions include various coal tar oils, light anthracene oil and other mineral coal tar fractions; certain highly aromatic petroleum hydrocarbon fractions such as the residues of hydrocracked West Texas heavy gas oil, catalytic cycle oils and hydroforming bottoms.

As stated heretofore, but a minor amount of the cracking inhibitor should be added. Advantageous results can be secured in some cases with as little as 0.01 per cent by weight of cracking inhibitor or less, and in all cases the amount of cracking inhibitor should not be more than 5 per cent by weight of the feed. Concentrations of cracking inhibitor in excess of 5 per cent by weight of the feed do not result in any further retarding of cracking, and may often lead to contamination and/or excessive carbon lay-down on the catalyst. Preferably the amount of added cracking inhibitor should be from 0.1 to 3 weight per cent of the feed, and/or should be adjusted so that it is in vapor phase at the reaction conditions.

The process of our invention is conducted in the presence of a solid catalyst. Suitable solid catalysts for this purpose include the conventional hydrogenation catalysts such as metals and metal compounds of groups Va, VIa, and of the iron group of the periodic table. Examples of these catalysts include vanadium oxide, molybdenum sulfide, molybdenum oxide, tungsten sulfide, iron, cobalt, nickel, nickel oxide, iron sulfide, nickel tungstate, cobalt molybdate, etc. These catalysts can be supported upon a carrier such as bauxite, alumina, silica-alumina, activated clays, titania, etc.

The process of our invention is conducted at a tem-

perature of about 700° to 1100° F. with a temperature of about 775° to 1000° F. being preferred. High reaction pressures in excess of about 50 pounds per square inch are employed, such as 50, 100, 300, 500, 1000, 1500, 2000, or 3000 pounds per square inch or more. It is preferable, particularly when isomerizing relatively high molecular weight hydrocarbons, that the partial pressure of the hydrogen comprise in excess of 50 per cent of the total reaction pressure, although lower partial pressures of hydrogen can be used. As indicated heretofore there is no appreciable consumption of hydrogen in the process of our invention, although in the case of a cracking inhibitor which is not a hydrogenated compound, some hydrogen will be consumed in saturating the cracking inhibitor. Thus, if anthracene is used as the cracking inhibitor, at least a portion of it will be hydrogenated to octahydroanthracene with a concomitant consumption of hydrogen. Depending upon the temperature and pressure, there may be some hydrocracking. In addition, at low pressures and high temperatures some aromatization of paraffins and some dehydrogenation of naphthenes may occur. However, the presence of the cracking inhibitors of our invention materially retards at least such hydrocracking.

By way of example we shall illustrate the process of our invention as applied to the isomerization of n-butane to isobutane. The degree of cracking normally encountered when isomerizing butane was determined by adding 62 parts by weight of n-butane, 74 parts by weight of a reduced tungsten disulfide (WS₂) catalyst and about 6.5 parts by weight of hydrogen to a bomb, and heating the charged bomb to a reaction temperature of about 800° F. for 2 hours. The average pressure within the bomb at reaction temperature was about 1900 pounds per square inch gauge.

This yielded a product containing 29.3 weight per cent of isobutane, 50.5 weight per cent of unreacted n-butane with the remaining 20.2 weight per cent comprising cracked and dehydrogenated material such as butenes, propane, ethane and methane.

In order to illustrate the cracking inhibition effect of anthracene, 56 parts by weight of n-butane and 0.6 parts by weight of anthracene (an anthracene concentration of about 1.07 weight per cent based on the n-butane) plus similar amounts of tungsten disulfide catalyst and hydrogen as used in the preceding experiment were charged to the bomb, and the bomb heated to the reaction temperature of about 800° F. for 2 hours as before. The average pressure in the bomb at the reaction temperature was again about 1900 pounds per square inch gauge.

The instant product contained about 26.0 weight per cent of isobutane and 62.2 weight per cent of unreacted n-butane, with but 11.8 weight per cent of cracked and dehydrogenated material. It is to be noted that a portion of the cracked material was derived from the anthracene.

It is seen from the foregoing that the addition of about 1 per cent by weight of anthracene based on the n-butane modified the products so as to give a reduction of cracked and dehydrogenated material of the order of about 40 weight per cent.

The foregoing bomb runs were effected with a very active catalyst and produced relatively high yields of both isobutane and cracked materials. Similar experiments were also conducted in which a less active catalyst comprising about 17.4 weight per cent of tungsten disulfide impregnated on a synthetic silica-alumina base was substituted for the tungsten disulfide catalyst. When 54 parts by weight of n-butane, 22 parts by weight of catalyst, and approximately the same amount of hydrogen as used in the afore-mentioned experiments were charged to a bomb, and the bomb maintained at a reaction temperature of about 800° F. for a period of about 4 hours (the pressure at the reaction temperature was about 1870 pounds per square inch gauge), a product consisting of 12.5 weight per cent of isobutane and 77.8 weight per cent of

unconverted n-butane was obtained, with the remaining 9.7 weight per cent comprising cracked and dehydrogenated material.

In an identical experiment in which 61 parts by weight of n-butane and 3 parts by weight of anthracene were charged to the bomb (an anthracene concentration of about 4.92 weight per cent based on the n-butane), a yield of about 11.3 weight per cent of isobutane and 84.9 weight per cent of unreacted n-butane was obtained, with the remaining 3.8 weight per cent of product comprising cracked and dehydrogenated material. It is to be emphasized that at least a portion of this 3.8 weight per cent of cracked material was derived from the anthracene. Similar results have been obtained in analogous experiments involving other feeds such as n-heptane.

It is obvious that our invention may be modified by one skilled in the art and it is to be understood that these modifications are included within the appended claims. By way of example, such modifications include

20 the substitution or addition of other catalysts. Moreover, other saturated hydrocarbon feeds, cracking inhibitors, and reaction conditions such as temperature and pressure, than those heretofore indicated that are readily apparent to one skilled in the art may be substituted for those specifically mentioned. It is also to be noted that while we have described the process of our invention as applied to batch procedure, namely bomb runs, it is equally applicable to a continuous procedure, as will readily be apparent to one skilled in the art.

30 Moreover, when the process of our invention is applied to a continuous procedure, optimum results can be secured by adding the cracking inhibitor to the charge prior to pre-heating the charge to the isomerization temperature, and at a temperature below the isomerization temperature.

35 The advantage of proceeding in this manner is readily apparent from the fact that when 175 parts by weight of cetane and about 8.75 parts by weight of hydrogen were heated together in a bomb to a temperature of about 800° F. for 70 minutes, sufficient hydrocracking occurred

40 to give a product comprising about 6.3 weight per cent of gas and 35.8 weight per cent of low-boiling liquid. The presence of but 0.15 weight per cent of anthracene based on the amount of cetane reduced the hydrocracking under these conditions so that the product contained but about 1.4 weight per cent of gas and 11.1 weight per cent of low-boiling liquid. When 0.75 weight per cent of anthracene was present, the hydrocracking was further reduced to give a product containing but about 0.8 weight

45 per cent of gas and 5.5 weight per cent of low-boiling liquid. Similarly, 1 weight per cent of quinoline based on the amount of cetane under identical conditions reduced the hydrocracking to a level where the product contained but 1.1 weight per cent of gas and 8.9 weight

50 per cent of low-boiling liquid. It is seen from the foregoing that thermal hydrocracking as well as catalytic hydrocracking is markedly reduced by the presence of minor amounts of the cracking inhibitors of our invention, and accordingly the avoidance of thermal hydro-

55 cracking by the addition of cracking inhibitor to the saturated hydrocarbon feed prior to elevating it to a temperature at which a significant degree of thermal hydrocracking is encountered is to be considered a part of our invention.

60 The process of our invention permits the isomerization of saturated hydrocarbons without any substantial degree of cracking, even though the isomerization is conducted at relatively high temperatures such as of the order of 700° to 850° F.

65 We claim:

1. In an isomerization process in which a saturated hydrocarbon is isomerized in the presence of hydrogen without any appreciable consumption of the hydrogen by contact with a hydrogenation catalyst selected from the group consisting of vanadium oxide, molybdenum sulfide,

molybdenum oxide, tungsten sulfide, iron, cobalt, nickel, nickel oxide, iron sulfide, nickel tungstate, and cobalt molybdate at an isomerization temperature of about 775° to 1000° F. and a pressure in excess of about 50 pounds per square inch, the improvement which comprises inhibiting the cracking of said saturated hydrocarbon by adding to it a minor amount of a polynuclear condensed ring compound selected from the group consisting of the trinuclear carbocyclic aromatic compounds, the binuclear heterocyclic nitrogen aromatic compounds, and their hydrogenated derivatives, the amount of said added polynuclear condensed ring compound being not more than 5 per cent by weight of the saturated hydrocarbon.

2. A process in accordance with claim 1 in which the saturated hydrocarbon is a straight chain hydrocarbon having from 4 to 12 carbon atoms.

3. A process in accordance with claim 1 in which the added polynuclear condensed ring compound is anthracene.

4. A process in accordance with claim 1 in which the added polynuclear condensed ring compound is phenanthrene.

5. A process in accordance with claim 1 in which the added polynuclear condensed ring compound is quinoline.

6. A process in accordance with claim 1 in which the added polynuclear condensed ring compound is acridine.

7. A process in accordance with claim 1 in which the added polynuclear condensed ring compound is indole.

8. A process in accordance with claim 1 in which the polynuclear condensed ring compound is added in an amount of from 0.1 to 3 per cent by weight.

9. A process in accordance with claim 1 in which the polynuclear condensed ring compound is in vapor phase at the isomerization temperature.

10. In an isomerization process in which a saturated hydrocarbon is isomerized in the presence of hydrogen without any appreciable consumption of the hydrogen by contact with a hydrogenation catalyst selected from the group consisting of vanadium oxide, molybdenum sulfide, molybdenum oxide, tungsten sulfide, iron, cobalt, nickel, nickel oxide, iron sulfide, nickel tungstate, and cobalt molybdate at an isomerization temperature of about 775° to 1000° F. and a pressure in excess of about 50 pounds per square inch, and in which the partial pressure of the hydrogen comprises in excess of 50 per cent of the total reaction pressure, the improvement which comprises inhibiting the cracking of said saturated hydrocarbon by adding to it a minor amount of a polynuclear condensed ring compound selected from the group consisting of the trinuclear carbocyclic aromatic compounds, the binuclear heterocyclic nitrogen aromatic compounds, the trinuclear heterocyclic nitrogen aromatic compounds, and their hydrogenated derivatives, the amount of said added polynuclear condensed ring compound being not more

than 5 per cent by weight of said saturated hydrocarbon.

11. In an isomerization process in which a saturated hydrocarbon is isomerized in the presence of hydrogen without any appreciable consumption of the hydrogen by contact with a hydrogenation catalyst selected from the group consisting of vanadium oxide, molybdenum sulfide, molybdenum oxide, tungsten sulfide, iron, cobalt, nickel, nickel oxide, iron sulfide, nickel tungstate, and cobalt molybdate at an isomerization temperature of about 775° to 1000° F. and a pressure in excess of about 50 pounds per square inch, the improvement which comprises inhibiting the cracking of said saturated hydrocarbon by adding to said saturated hydrocarbon a minor amount of a polynuclear condensed ring compound selected from the group consisting of the trinuclear carbocyclic aromatic compounds, the binuclear heterocyclic nitrogen aromatic compounds, the trinuclear heterocyclic nitrogen aromatic compounds, and their hydrogenated derivatives prior to heating said saturated hydrocarbon to said isomerization temperature and at a temperature below said isomerization temperature, the amount of said polynuclear condensed ring compound being not more than 5 per cent by weight of said saturated hydrocarbon.

12. A process in accordance with claim 11 in which the saturated hydrocarbon is a straight chain hydrocarbon having from 4 to 12 carbon atoms.

13. A process in accordance with claim 11 in which the added polynuclear condensed ring compound is anthracene.

14. A process in accordance with claim 11 in which the added polynuclear condensed ring compound is phenanthrene.

15. A process in accordance with claim 11 in which the added polynuclear condensed ring compound is quinoline.

16. A process in accordance with claim 11 in which the added polynuclear condensed ring compound is acridine.

17. A process in accordance with claim 11 in which the added polynuclear condensed ring compound is indole.

18. A process in accordance with claim 11 in which the polynuclear condensed ring compound is added in an amount of from 0.1 to 3 per cent by weight.
